(Continued)

Primary Examiner — Janice Patyk*Assistant Examiner* — Ji Sun Yoon(74) *Attorney, Agent, or Firm* — Ricky Lam(57) **CLAIM**

The ornamental design for a cooler bag, as shown and described.

DESCRIPTION

FIG. 1 is a front perspective view of a cooler bag, showing my new design;

FIG. 2 is a rear perspective view thereof;

FIG. 3 is a front view thereof;

FIG. 4 is a rear view thereof;

FIG. 5 is a left side view thereof;

FIG. 6 is a right side view thereof;

FIG. 7 is a top view thereof;

FIG. 8 is a bottom view thereof;

FIG. 9 is an enlarged detail view of area 9 in FIG. 1 thereof; and,

FIG. 10 is an enlarged detail view of area 10 in FIG. 2. The broken lines in the drawings illustrate portions of the cooler bag that form no part of the claimed design.

The dash-dot-dash broken lines of FIGS. 1, 2, 9, and 10 are included to show partially enlarged views only and form no part of the claimed design.

1 Claim, 10 Drawing Sheets(56)
